CLAIM

The ornamental design for a food basket for a golf cart, as shown and described.

DESCRIPTION

FIG. 1 is a top, front perspective view of a food basket for a golf cart showing the claimed design;

FIG. 2 is a bottom, rear perspective view thereof;

FIG. 3 is a right side view thereof;

FIG. 4 is a front view thereof;

FIG. 5 is a left side view thereof;

FIG. 6 is a rear view thereof;

FIG. 7 is a top view thereof; and,

FIG. 8 is a bottom view thereof.

The dash-dot-dash broken lines shown in FIGS. 1-8 are boundaries of the claimed design and form no part of the claimed design.
